MACHINE FOR BLENDING WOOL

Filed Feb. 4, 1948

UNITED STATES PATENT OFFICE

2,646,597

MACHINE FOR BLENDING WOOL

Jack Dunbar Townsend, Lowry Bay,
New ZealandApplication February 4, 1948, Serial No. 6,312
In New Zealand January 24, 1947

9 Claims. (Cl. 19—96)

1

The invention relates to machines for performing the operation of what is commonly referred to as the blending of wool, for the purpose of enhancing the commercial value of same, and which consists in opening out the wool and ensuring the intimate mixing of the constituent fibres of portions of varying shades or colours so as to give the wool a more or less uniform appearance throughout, with portions thereof of less desirable appearance so distributed through the wool that the latter in bulk is of improved appearance.

Known machines provided for the aforesaid purpose comprise rotary drums with rows of teeth thereon, operating over grids, the wool to be dealt with being fed between fluted feed rollers from which the wool passes to the toothed drums and is acted upon solely by the teeth thereof while passing from the feed rollers, which are fixed as regards distance from the drums, and which give rise to the objection that all wools of varying lengths of staple are not able to be successfully dealt with by the same machine.

The object of the invention is to provide improvements in the aforesaid type of machine, so as to enable one machine to successfully deal with wools of varying lengths of staple, irrespective of whether the blending is to be performed by the opening out and intimate mixing of different portions of the same wool or of different wools.

A wool blending machine provided with the improvements comprising the invention, incorporates one or a plurality of toothed drums, adapted to operate over grids and in conjunction with feed rollers, and is characterised by the provisions of means, capable of being adjusted towards or from the drum teeth in accordance with the length of staple of the wool under treatment, for the purpose of retarding the wool against the action of the drum teeth.

In one instance, the wool retarding means can comprise feed rollers capable of being adjusted towards or from the drum teeth, and in another instance, said wool retarding means can comprise stationary teeth, capable of being adjusted towards or from the drum teeth.

The accompanying drawing illustrates the application of the improvements to a wool blending machine,

Figure 1 being an elevation of the machine with the side doors and machinery guard removed, and

Figure 2 is a plan view of same with the covers removed, while

2

Figures 3 and 4 are detail views illustrating the form and arrangement of the drum teeth and the stationary teeth, and

Figures 5 and 6 are detail views of the mechanism for raising and lowering the grid frame in order to obtain adjustment of the stationary teeth.

As illustrated, the machine comprises a main frame 1 having mounted thereon by means of cross shafts 2 and bearings 3, a primary drum 4 and a secondary drum 5, adapted to be rotated in the direction indicated by the arrows in Figure 1, by belt drives applied to pulleys 6 on the shafts 2.

Each drum 4 and 5 has secured to and spaced equi-distantly around its periphery, rows of teeth 7 shaped as illustrated in Figure 3, the number of rows of teeth on drum 5 differing from the number of rows on the other drum, so as to insure more effective blending of the wool.

The drums 4 and 5 are finely balanced and are machined perfectly true at their peripheries, the teeth 7 on each and both drums being in perfect alignment through the length of the machine and being designed to avoid damaging the wool.

Fluted feed rollers 8 disposed one above the other are provided adjacent the primary drum 4 at the feed end of the machine, the bearings for the upper roller 8 being adjustable in the same housing 9 as the bearings for the lower roller 8, and being maintained in contact with the latter by spring means in conventional manner, such arrangement and mounting of the feed rollers allowing for rise and fall of the upper roller 8 to suit the quantity of wool going through the rollers 8 to the drum 4.

The feed rollers are driven through a crossed belt reduction drive 10 from the shaft 2 of the primary drum 4, and reduction chain drives 11, to the shaft of the lower roller 8.

Wool to be processed by the machine, is delivered to the feed rollers 8, by an endless conveyor 12, made to pass around rollers 13, which with the housings 9 for the bearings of the feed rollers 8, are mounted on a secondary frame 14 slidable on the main frame 1 towards or from the primary drum 4.

The endless conveyor 12 can be of any suitable form, its front roller 13 being driven through a chain drive 15 from the opposite end of the shaft of the lower feed roller 8 to which the drive 11 is applied.

The location of the front roller 13 of the conveyor 12 as regards clearance from the feed roll-

ers 8, to suit the type of conveyor 12 being used, is capable of adjustment by screw adjusting means at 16, while similar adjusting means can be provided at 17 to tension the conveyor 12 as required, while undue sagging of the upper side of the conveyor 12 can be prevented by means of a rigid spreader plate support.

The feed rollers 8 are capable of being adjusted towards or from the toothed primary drum 4, to provide for the treatment of wools having staples of varying lengths, by the teeth 7 of the drum 4, while the wools are still gripped by and as they pass between the feed roller 8, by sliding the frame 14 on the main frame 1, screw locking means 18 being provided between the frame 14 and the frame 1, to maintain the former in a selected position on the latter, and as the rollers 13 and housings 9 are all mounted on the frame 14, the relationship of the conveyor 12 to the feed rollers 8, and the tensioning of the conveyor 12, are not affected by alteration of the location of the rollers 8 in relation to the drum 4.

The provision of feed rollers 8 adjustable as aforesaid, enables a considerable range of wools of long and comparatively short staples to be successfully dealt with, but where the wool staple is so short that even with the feed rollers 8 adjustable as aforesaid, the desired treatment can not be effected, provision is made for the opening out and mixing of the wool portions or wools, to be performed between the teeth 7 of the drums 4 and 5 and other teeth 19 held stationary during the operation of the drums 4, 5.

As previously mentioned, the teeth 7 on the drums 4, 5 are in rows thereon, and the stationary teeth 19 are also in rows, the latter being positioned and held, and the teeth 19 thereof so spaced, that the teeth 7 of the drums 4, 5 pass between them, the spaces between the moving teeth 7 and the stationary teeth 19 being such that the wool is thoroughly dealt with to effect the blending without detriment thereto.

Provision is made for adjusting the stationary teeth towards or from the drums 4, 5 to suit different lengths of wool, or to so position said stationary teeth 19 that they will take no part in the operations—as, for instance, where the wool is wholly dealt with by the teeth 7 on the drum 4, while gripped by the feed rollers 8.

One or more toothed rotary drums can be employed, and there may be one or more rows of stationary teeth 19 in relation to each drum, said last mentioned rows being mounted on a frame 20, and spaced about the peripheries of the drums 4, 5.

The frame 20 is adjustable vertically in the frame 1 to bring the teeth 19 into the desired relationship with the teeth 7 of the drums 4, 5, or to cause the teeth 19 to be lowered completely clear of the teeth 7. Vertical adjusting screws 21 held in brackets 22 on the frame 1 are operated through nuts 23 secured on brackets 24 of the frame 20. The screws 21 are geared together by bevel gearing 25 and shafts 26 on both sides of the frame 1. All the screws 21 can be operated simultaneously from a single operating point on cross shaft 27 which is operably connected to each shaft 26 to raise or lower the frame 20, evenly.

Locking bolts 28 provided on the frame 20 and adapted to operate in vertical slots 29 in vertical members of the frame 1, provide means for securing the frame 20 with the teeth 19 thereon in a selected position, and also for limiting movement of the frame 20.

Grids comprising a grating made up of a plu-

rality of parallel bars indicated at 30 are provided on the frame 20 between the rows of teeth 19 and at the sides of the latter to conform to the contour of the drums, said grids 30 being of any suitable formation and being interchangeable as required, the provision of the grids allowing loose dirt and foreign matter removed from the wool, to be disposed of, and so avoid same finding its way later into the scouring liquor.

10 The machine can be provided with a conveyor for discharging blended wool from the machine, and with necessary casing, guards, control means and other parts essential for its operation.

15 What I do claim and desire to obtain by Letters Patent of the United States of America is:

1. A wool blending machine including a main frame, at least one drum rotatably mounted on the frame, rows of teeth carried by the drum, another frame mounted for vertical movement in the main frame and positioned beneath the drum, spaced rows of stationary teeth supported on the last mentioned frame and adjustable therewith for coacting with the teeth on the drum, grids on opposite sides of the rows of teeth on the last mentioned frame, and means for adjusting said last mentioned frame including a plurality of screws and means gearing the screws together for simultaneous operation.

2. A wool blending machine including a main frame, at least one rotatable drum on the frame, another frame mounted on the main frame and adjustable vertically with respect to the main frame and including spaced grids arranged adjacent the periphery of the drum, wool retarding means comprising cooperating rows of teeth, respectively on the periphery of the drum and on the last mentioned frame between the grids, an additional frame laterally slidably mounted on said main frame in advance of said drum, adjustable feed rollers carried at the end of said latter frame adjacent the drum and adjustable conveying means carried by said latter frame outwardly of said feed rollers.

3. A wool blending machine including a main frame, at least one rotatable drum on said frame, another frame mounted on the main frame and adjustable vertically with respect to the main frame and including spaced grids arranged adjacent the periphery of the drum, wool retarding means comprising cooperating rows of teeth, respectively on the periphery of the drum and on the last mentioned frame between the grids, means for raising and lowering the movable frame including spaced brackets mounted on both sides of both frames, vertically disposed screws mounted in the brackets on the main frame and adjustably engaged with the brackets on the movable frame, a drive shaft journaled in the brackets on both sides of the main frame, and intermeshing gears carried by the shafts and the respective screws so that when the shafts are rotated the screws will be rotated to correspondingly raise or lower the movable frame.

4. A wool blending machine including a main frame, at least one toothed drum rotatably mounted on the main frame, a secondary frame slidable longitudinally on the top of the main frame in advance of the drum, superposed feed rollers mounted at the inner end of the secondary frame for cooperating with the toothed drum, a horizontally disposed endless feeding conveyor mounted on the secondary frame, longitudinally spaced rollers supporting the conveyor, independent screw means on the secondary frame for adjusting each supporting roller for the conveyor

relative to the feed rollers to adjust the position of the conveyor relative to the feed rollers and to tension the conveyor, and screw adjusting and locking means provided between the secondary frame and the main frame for moving the secondary frame relative to the main frame to adjust the feed rollers relative to the drum without disturbing the adjustment of the conveyor relative to the feed rollers or the tension of the conveyor.

5. A wool blending machine as claimed in claim 4 in which another frame is vertically slidably mounted in the main frame beneath the drum, spaced grids carried at the top of said drum positioned in closely spaced relation to the other frame and spaced rows of teeth carried by said other frame and positioned between the grids for cooperating with the teeth on the drum.

6. A wool blending machine including a main frame, spaced toothed drums rotatably mounted thereon, a secondary frame slidably mounted on the top of the main frame in advance of the main drum, superposed feed rollers mounted at the inner end of the secondary frame for cooperating with the teeth on the adjacent drum, an endless conveyor mounted on the secondary frame, means on the secondary frame for adjusting the conveyor with relation to the feed rollers, means on the secondary frame for tensioning the conveyor, screw adjusting and locking means provided between the secondary frame and the main frame, a third frame mounted for vertical sliding movement beneath the drums, spaced grids carried by the top of the last mentioned frame and disposed in closely spaced relation to the lower peripheries of the drums, and rows of stationary teeth carried by the last mentioned frame and positioned between the grids for cooperating with the teeth on the drums and positioned so that the teeth on the drums will pass therebetween.

7. A wool blending machine as claimed in claim 6 in which the teeth on the drums are arranged in rows extending across and spaced around the drums, the teeth of said drums being in alignment through the length of the machine and the number of rows of teeth on one drum being different than the number of rows of teeth on the other drum.

8. A wool blending machine including a main frame, at least one toothed drum rotatably mounted on the main frame, a secondary frame slidable longitudinally on the top of the main frame in advance of the drum, superposed feed

rollers mounted at the inner end of the secondary frame for cooperating with the toothed drum, a horizontally disposed endless feeding conveyor mounted on the secondary frame, longitudinally spaced rollers for supporting the conveyor and about which the same passes, independent screw means carried by the secondary frame for adjusting each supporting roller for the conveyor relative to the feed rollers to adjust the position of 10 the conveyor relative to the feed rollers and to tension the conveyor, screw adjusting and locking means provided between the secondary frame and the main frame for moving the secondary frame relative to the main frame to adjust the feed 15 rollers relative to the drum without disturbing the adjustment of the conveyor relative to the feed rollers or the tension of the conveyor, an additional frame vertically slidably mounted on the main frame beneath the drum, spaced grids 20 carried at the top of said additional frame and conforming to the contour of the drum, spaced rows of teeth carried by said additional frame and positioned between the grids thereon for cooperating with the teeth on the drum, and means 25 for synchronously operating the feed rollers from the rotary drum.

9. A wool blending machine as defined in and by claim 8 and in which the said additional frame is vertically movably connected with the main 30 frame at a plurality of points, vertical screws at each point and means for gearing the screws together for simultaneous operation to move the additional frame and the stationary teeth carried thereby toward or from the drum for retarding 35 wool against the action of the drum teeth.
